CLAIM

The ornamental design for a display device for virtual reality (VR) experience, as shown and described.

DESCRIPTION

FIG. 1 is a front, right perspective view of the display device for virtual reality (VR) experience showing my new design with a screen located within a main body;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right perspective view of the display device for virtual reality (VR) experience with the screen extended from the main body;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.
